IGNITER BUSHING

Joseph H. Cox, Forest Hills, Pa., assignor to Westinghouse Electric & Manufacturing Company, East Pittsburgh, Pa., a corporation of Pennsylvania

Application July 12, 1940, Serial No. 345,084

5 Claims. (Cl. 250—27.5)

My invention relates to a vapor electric device and particularly to a lead-in connection for the make-alive electrodes of vapor electric valves.

Considerable difficulty has been experienced in securing the proper location of the make-alive electrodes in respect to the mercury surface in vapor electric devices. According to my invention, the make-alive electrode is mounted by means of a flexible diaphragm sealed in vacuum-tight relation to the container of the valve and means provided for flexing the diaphragm to shift the location of the make-alive with respect to the cathode surface.

It is accordingly an object of my invention to provide an adjustable mounting for a make-alive electrode.

It is a further object of my invention to provide a suitable vacuum-tight seal for the entrance bushing of a make-alive electrode.

Other objects and advantages of my invention will be apparent from the following detailed description taken in conjunction with the accompanying drawings in which:

Figure 1 is an elevation partially in section of a vapor electric valve showing my improved make-alive connection.

Fig. 2 is a detailed sectional view of an entrance bushing referring to my invention; and

Fig. 3 is an elevation showing in detail the construction of the adjusting screws.

The illustrated embodiment of my invention of a vapor electric device comprises a suitable container 1 having a mercury cathode 2 and a cooperating anode 3 therein. If desired, the anode 3 may be protected by a suitable shield 4. A make-alive electrode 5 is mounted in an opening 6 in the side of the container 1 which is preferably provided by welding a tubular sleeve 7 into the side of the container 1, said sleeve 7 having a flange 8 adjacent the outer end thereof. The flange 8 is provided with a mounting ring 9 for receiving the bushing presently to be described.

The entrance bushing comprises a tubular supporting member 10 to the outer end of which is secured preferably by projection welding an annular flexible diaphragm 11, preferably of a metal, such as "Kovar," to which a glass seal may be readily attached. Usually a hub 12 is interposed between the supporting sleeve 10 and the diaphragm 11 in order to facilitate making the weld and to add a proper bearing surface on the diaphragm 11.

Adjacent the inner end of the supporting sleeve 10 a suitable insulating bushing 13 is

provided for spacing the lead-in conductor 14 from contact with the metal sleeve 10. The insulator 13 is, in turn, provided with shielding members 15 and 16 to prevent the bridging of the insulator 13 by material sputtered into or onto the lead-in or insulating member. Preferably the shields 15 and 16 form a labyrinth disposed in two spaced-apart annular members, one being spaced from the lead-in conductor and secured to the inner end of the sleeve and the other being secured in any suitable manner to the lead-in conductor. The outer end of the lead-in bushing is composed of a cap-like metallic member 17 preferably welded to the lead-in conductor 14 and being joined in insulating relation to the flexible diaphragm 11 by means of a glass seal 18.

In order to protect the glass seal 18 and to provide a control member for the lead-in bushing, a guide sleeve 19 is secured to the exterior of the flexible diaphragm 11 preferably by means of a hub 20 in spaced relation to the lead-in conductor 14 and the glass seal 18 therefor.

A connection 21 is applied to the outer end 17 of the lead-in conductor 14 in any desired manner preferably by welding or brazing to the external end 17 of the lead-in conductor 14.

In order to secure the flexible diaphragm 11 in vacuum-tight relation to the flange 8, the flange 8 is provided with suitable grooves 22 in which endless rings 23 of suitable deformable metal are placed. The mounting ring 9 is placed on a seat 24 on the flange 8 after which the diaphragm 11 is placed in position and pressed into firm contact with the deformable rings 23 by means of a cap 25 preferably secured to the flange 8 by means of bolts or screws 26. The ring 9 not only positions the support 10 but reinforces the diaphragm against excessive distortion by the atmospheric pressure.

To provide the adjusting mechanism for the lead-in bushing, the cap 25 is provided with lugs or projections 27, in which setscrews 28 are placed which make contact with pivot blocks 29 on the guide sleeve 19. The make-alive electrode 5 can then be adjusted with respect to the cathode surface by changing the position of the setscrews 28.

If desired, the external end of the bushing may be closed by a suitable insulating member 30 to prevent mechanical damage by accidental contact with the protruding connection 21 to the lead-in member 14.

While, for purposes of illustration, I have shown and described a specific embodiment of

my invention, it will be apparent that changes and modifications can be made therein without departing from the true spirit of my invention and the scope of the appended claims.

I claim as my invention:

1. An adjustable mounting for carrying a lead-in connection for a make-alive electrode through an opening in a metal container comprising a flange about the opening, a flexible metal diaphragm mounted in vacuum-tight relation to said flange, a reenforcing ring for said diaphragm, a hub welded to said diaphragm, a tubular supporting member rigidly connected to said hub, a lead-in rod extending through said supporting member and said diaphragm, a make-alive electrode mounted on said rod, a glass seal between said rod and said diaphragm, an insulating bushing for holding said rod in spaced relation to said supporting member, a shield for said insulating bushing, a second hub secured to said diaphragm, a tubular guide secured to said second hub and screws contacting said guide member for adjusting the position of the make-alive electrode.

2. A vapor electric device comprising a container having an opening therein, a liquid cathode in said container, a make-alive electrode having a tip portion immersed in said cathode, a lead-in rod supporting the make-alive electrode, said rod extending through the opening in the container, a flexible metallic diaphragm sealed in vacuum-tight relation to said opening, a tubular support secured to said diaphragm, the tubular support being spaced from said rod, an insulating bushing between said support and said rod, shield members for said insulating bushing, a vacuum-tight insulating seal between said diaphragm and said rod, a guide member secured to said diaphragm and adjusting means cooperating with said guide member for controlling the amount of immersion of said make-alive electrode in said cathode.

3. A lead-in bushing for adjustably passing

the lead-in connection of a make-alive electrode through an opening in a container comprising a flexible diaphragm sealed to the container, a supporting member connected to said diaphragm, a lead-in rod extending through said diaphragm, a make-alive electrode mounted on said rod, an insulated bearing between said rod and said supporting member, a vacuum-tight seal between said rod and said diaphragm, a guide member secured to said diaphragm and adjusting means cooperating with said guide member.

4. A lead-in bushing for passing a make-alive lead-in through an opening in the container of an electric valve comprising a flexible diaphragm sealed to the container, a supporting member connected to said diaphragm, a lead-in rod extending through said diaphragm, a make-alive electrode carried by said rod, an insulated bearing between said rod and said supporting member, a protective shield for said rod, a vacuum-tight seal between said rod and said diaphragm, a guide member secured to said diaphragm and adjusting means cooperating with said guide member for controlling the position of the make-alive electrode.

5. A lead-in bushing for the make-alive electrode of a vapor electric device having an opening for insertion of the lead-in comprising a lead-in member, a make-alive electrode supported thereby, a flange connected to the vapor electric device about the opening, a reenforcing ring seated on the flange, a flexible diaphragm mounted adjacent said reenforcing ring, means for sealing said diaphragm in vacuum-tight relation to said flange, a supporting member rigidly secured to said diaphragm, an insulating member maintaining said lead-in in spaced relation from said supporting member, a guide member rigidly secured to said diaphragm and means for adjusting the guide member to control the position of the make-alive electrode in said vapor electrode device.

JOSEPH H. COX.
